UNITED STATES PATENT OFFICE.

GEORGE LEDER, OF DEMOPOLIS, ALABAMA.

OIL-MAT.

SPECIFICATION forming part of Letters Patent No. 257,728, dated May 9, 1882.
Application filed March 31, 1882. (No model.)

To all whom it may concern:

Be it known that I, GEORGE LEDER, of Demopolis, in the county of Marengo and State of Alabama, have invented certain new and useful Improvements in Oil-Mats; and I do hereby declare the following to be a full, clear, and exact description of the invention, such as will enable others skilled in the art to which it pertains to make and use the same.

10 My invention relates to an improvement in oil-mats adapted more particularly for use in expressing cotton-seed oil; and it consists mainly in the construction and arrangement of a grooved and perforated edging rigidly secured to a metallic oil-mat, as will be herein-after more fully explained and set forth.

Heretofore and at present, in cotton-seed oil mills, the cotton-seeds are first cleaned, ginned, and hulled, after which they are crushed 20 and subjected to heat for the purpose of expelling dampness and moisture from the crushed seeds, which are then filled into sacks of the desired size, made of press-cloth. These sacks are then placed in hair or metallic mats, 25 which latter are placed in suitable boxes and subjected to pressure of about three thousand five hundred or four thousand pounds to the square inch, during which a part of the oil is expressed from the seeds. The sacks before 30 referred to each contain about thirteen pounds of the kernels, which yield about two and three-quarters pounds of oil, leaving a residuum of about ten and one-quarter pounds of meal or oil-cake. The hair mat, after being used a while, 35 has a tendency to stretch or elongate and widen, and it becomes too large for the box above referred to, in consequence of which the kernels at the ends which project outside the box do not receive the full pressure, and there 40 is a consequent loss of about one ounce of oil in the mat, which is about three per cent. of the entire yield from a single mat at one pressing. When pressure is applied to the hair mats there is not sufficient escape for the contained 45 air, which bursts the sack, and soon becomes unfit for use.

The objection to the use of the metallic mats heretofore employed is that they afford no sufficient means for preventing the bag from 50 stretching beyond the sides of the mat, which renders it liable to the objections before noted, and where they do employ side flanges or

ridges for the purpose of preventing the sack from stretching they are deficient in means of egress for the oil and air, which renders them 55 unfit for the purposes in view.

The object of this present invention is to overcome some of the objections above noted by providing a metallic mat adapted to receive the sack, and provided with side ridges 60 having transverse slots and longitudinal grooves for the escape of the oil and air.

In the accompanying drawings, Figure 1 is a perspective view, showing my mat in partly-open adjustment; and Fig. 2 is a transverse 65 sectional view of the same in closed adjustment.

The mat is made of any suitable metal, and consists of the two leaves A, about five-eighths of an inch thick and of any suitable size, secured together by the flexible hinge B. Each leaf or plate A is provided on its internal face with the side strips or flanges, C, made of any suitable metal, and formed integral with the leaves A, or rigidly secured thereto by riveting 70 or otherwise, and each ridge or strip C is transversely perforated at suitable distances apart for the passage of the oil and air. The perforations a are situated in the same horizontal plane with the inner faces of the plates A, so 75 as to enable the oil to freely flow from the mats as soon as it is expressed from the contained kernels. A longitudinal groove or passage, D, extends between each flange C and its corresponding plate A, one half of the said groove 80 being formed in the said plate A, while the other half thereof is formed in the side flange, C. This groove D is about three-eighths of an inch wide and about one-eighth of an inch deep, which size is sufficient to enable the oil to pass 85 from the mats as soon as it is expressed from the seeds. The transverse perforations a are about one inch apart, semicircular in shape, and about one-half the size of the groove or 90 passage D. The object of these grooves and holes is to admit of the escape of air and oil, 95 while the side flanges, C, prevent the sacks from spreading, which causes a loss of oil, as before described.

These metallic mats, being considerably 100 smaller in size than the hair mats, enable two or more of the former to be placed in the press-box instead of one of the latter, and thereby increase the yield proportionately.

In these metallic mats there is no possible stretching, which allows full and complete pressure to be extended on all parts of the sack, which expresses the oil from the seeds in all parts of the sack alike, and thereby saving about three percent, which was heretofore lost by the stretching of the mat.

The longitudinal groove D, before referred to, passes centrally through the transverse perforations a, and is large enough to carry off the oil as fast as it is expressed, and hence all danger of clogging of the parts caused by the mats fitting up closely against the sides of the box and stopping the flow of oil therefrom is obviated. As fast as the oil is expressed from the seeds it flows through the transverse perforations into the longitudinal slot D, and from thence it passes to the receiver from both ends of the slots D.

Having fully described my invention, what I claim as new, and desire to secure by Letters Patent, is—

A mat for expressing oil, composed of two metallic leaves hinged together at one end, each leaf being provided with two side flanges 25 or ridges, and each side flange or ridge being traversed by transverse and longitudinal grooves, substantially as and for the purpose hereinbefore described.

In testimony whereof I have signed this 30 specification in the presence of two subscribing witnesses.

GEORGE LEDER.
